United States Patent Office

Des. 211,867
Patented Aug. 6, 1968

211,867

SLED

Richard L. Trumely, Charlotte, Mich., assignor to General Aluminum Products, Inc., Charlotte, Mich., a corporation of Michigan

Filed Sept. 13, 1967, Ser. No. 8,582

Term of patent 14 years

(Cl. D14—24)

FIG. 4.

FIG. 5.

FIG. 1 is a frontal, perspective view of the sled;
FIG. 2 is a side-elevation thereof;
FIG. 3 is a front elevation thereof;
FIG. 4 is rear elevation thereof; and
FIG. 5 is a plan view thereof.

I claim:

The ornamental design for a sled, substantially as shown.
